STEAM GENERATORS

Kenneth Thomas Disley, Addington, England, assignor to
Foster Wheeler Corporation, Livingston, N.J., a cor-
poration of New York

Filed Apr. 4, 1966, Ser. No. 552,357
5 Claims. (Cl. 122—480)

ABSTRACT OF THE DISCLOSURE

A vapor generator for marine use including a division wall to form an inner radiant chamber and a convection chamber. A primary superheater is located within the inner radiant chamber. The outer convection chamber includes two compartments, one of which has a reheatere therein shielded by a secondary superheater.

It should be understood that the terms "water" and "steam" where used herein and in the claims are to be read generically to include any liquid and its vapor unless the context requires otherwise.

In marine boilers, reheaters are generally installed only in the ahead turbine drive and not in the astern drive. When running astern or maneuvering no steam passes through the reheatere and, unless special precautions are taken, the reheatere may be overheated and seriously damaged. A particular difficult situation arises where emergency astern running is necessary since then the boiler has to work at high power. A solution is to install the reheatere outside the boiler in an independently fired furnace but that is a complication which it is desirable to avoid.

In accordance with the invention, the boiler is provided with a primary superheater shielded from radiant heat and with a secondary superheater and a reheatere which are arranged in that order in the normal gas path from the steam generating section and with means for causing the gases to bypass the secondary superheater and the reheatere when desired. The bypass means may be adjustable so that the secondary superheater and the reheatere are bypassed by any desired proportion of the gases leaving the steam generating section. Normally after passing over or bypassing the secondary superheater and reheatere the gases will pass to an economizer or other heat recovery system.

The primary superheater may be shielded by being positioned in the steam generating section.

An example of a boiler in accordance with the invention is shown diagrammatically in the accompanying drawing, in which:

FIGURE 1 is a sectional elevation of the boiler; and FIGURE 2 is a sectional plan.

The boiler shown therein is a D-type marine boiler having a steam drum 10 and a water drum 12 connected by a bank of steam generating tubes 14 within which there is arranged a superheater 16 shielded by the said tubes from the fierce radiant heat of the furnace 18. An economizer 20 is arranged in the flue 22 for the waste gases.

The lower part of the flue has two parallel passages 24 and 25 (FIGURE 2). In the passage or reheatere compartment 24, there are arranged a secondary superheater 26 connected in series with the primary superheater 16 and a reheatere 28 receiving steam which has done useful work. These two appliances are well shielded from radiant heat by a wall 30 which stops short of the floor of the boiler. Dampers 36 are provided at the top of the passage 24.

In the passage or heat absorbing compartment 25, there is arranged a bank of steam generating tubes 29. Dampers

2

similar to the dampers 36 (not shown) are provided at the top of the passage 25. Normally these dampers and the dampers 36 will work in opposite, as one opens or opens partially the other closes or closes partially.

5 By appropriate adjustment of the dampers 36, the secondary superheater and the reheatere can be totally or partially bypassed by the gases passing to the flue.

Under normal operating conditions, i.e. steaming ahead, the gas path is from the furnace to the flue through the two passages 24 and 25 and by adjustment of the dampers the relative flow through the two passages can be adjusted to suit the particular steaming conditions obtained at that time. The reheatere is in a low temperature zone and is screened by the wall 30 and the secondary superheater 15 26. It therefore operates under very favorable conditions.

Under steaming astern or maneuvering conditions, the reheatere is not required and although it is in a relatively low temperature zone is still liable to being overheated, particularly in an emergency when the boiler may be required to work at its limit. By adjustment of the dampers 36, however, the gas path can be altered so that no gas or substantially no gas flows over the secondary superheater or the reheatere, the full weight or substantially the full weight of gas passing over the steam generating bank in the passage 25. The full weight of steam, however, passes through the secondary superheater and prevents the latter being overheated which, in turn, provide a relatively cool screen in front of the reheatere which is thus protected against overheating.

20 30 The economizer 20 can be replaced or supplemented by an air heater or by steam generating tubes.

For controlling the temperature of the steam and safeguarding the secondary superheater and the reheatere, steam can be drawn off in any desired amount from the 25 primary superheater and be returned thereto after passing through an attemperator coil 38 arranged in either the steam drum 10 (as shown) or in the water drum of the boiler.

The dampers 36 could, of course, be arranged at the 40 bottom of the passages 24 and 25.

The merit of the invention is that of producing a simple and compact installation which is of paramount importance in a marine boiler.

45 Although the invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

I claim:

1. A vapor generator comprising:
  - a setting having a furnace chamber therein, said furnace chamber having a floor;
  - means for firing said furnace chamber thereby producing combustion gases;
  - a division wall vertically located and having a lower end above the floor of said furnace chamber to form an opening to permit the flow of combustion gases under the division wall, said division wall separating said furnace chamber into an inner radiant chamber with said means for firing and an outer convection chamber;
  - a primary superheater located in said inner radiant chamber;
  - a bypass wall within said convection chamber and located at substantially right angles with said partition wall and also extending vertically upwardly, said bypass wall separating a portion of said convection chamber into a heat absorbing compartment and a reheat compartment;

a secondary superheater located in said re heater compartment;
a re heater located in said re heater compartment above
said secondary superheater;
heat absorbing means located in said heat absorbing 5
compartment; and
means for controlling the relative flow of gases between
said re heater compartment and said heat absorbing
compartment.

2. A vapor generator according to claim 1 wherein said 10
heat absorbing means is a bank of vapor generating
tubes.

3. A vapor generator according to claim 2 wherein said
means for controlling the relative flow of gases between
said re heater compartment and said generating compartment
is a plurality of dampers at the upper end of said 15
re heater compartment and at the upper end of said heat
absorbing compartment.

4. A vapor generator comprising:
a setting having a furnace chamber therein; 20
means for firing said furnace chamber thereby produc-
ing combustion gases;
a division wall vertically located and having a lower
end above the floor of said furnace chamber to form
an opening to permit the flow of combustion gases 25
under the division wall, said division wall separating
said furnace chamber into an inner radiant chamber
with said means for firing and an outer convec-
tion chamber;
a primary superheater located in said inner radiant 30
chamber;
a bypass wall within said convection chamber and lo-
cated at substantially right angles with said par-
tition wall and also extending vertically upwardly
from said primary superheater, said bypass wall 35
separating a portion of said convection chamber into
a heat absorbing compartment and a reheat com-
partment;
a secondary superheater located in said re heater com-
partment; 40
a re heater located in said re heater compartment above
said secondary superheater;
a bank of vapor generating tubes located in said heat
absorbing compartment; 45
a plurality of dampers at the upper end of said re heater
compartment and at the upper end of said heat ab-
sorbing compartment for controlling the relative
flow of gases between said re heater compartment
and said heat absorbing compartment; and 50

4
an economizer within said convection chamber above
said plurality of dampers and above said bypass wall;
5. A vapor generator comprising:
a setting having a furnace chamber therein;
means for firing said furnace chamber thereby produc-
ing combustion gases;

a division wall vertically located and having a lower
end above the floor of said furnace chamber to form
an opening to permit the flow of combustion gases
under the division wall, said division wall separating
said furnace chamber into an inner radiant chamber
with said means for firing and an outer convection
chamber;
a bank of vapor generating tubes located in said inner
radiant chamber;
a primary superheater located in said inner radiant
chamber and shielded by said bank of vapor generat-
ing tubes located in said inner radiant chamber;
a bypass wall within said convection chamber and lo-
cated at substantially right angles with said partition
wall and also extending vertically upwardly from said
primary superheater, said bypass wall separating a
portion of said convection chamber into a heat ab-
sorbing compartment and a reheat compartment;
a secondary superheater located in said re heater com-
partment;
a re heater located in said re heater compartment above
said secondary superheater;
a bank of vapor generating tubes located in said heat
absorbing compartment;
a plurality of dampers at the upper end of said re heater
compartment at the upper end of said heat absorbing
compartment for controlling the relative flow of
gases between said re heater compartment and said
heat absorbing compartment; and
an economizer within said convection chamber above
said plurality of dampers and above said bypass
wall.
